GRANT D. BRADSHAW, OF PITTSBURGH, PENNSYLVANIA, ASSIGNOR, BY MESNE ASSIGNMENTS, TO BLAW-KNOX COMPANY, OF BLAWNOX, PENNSYLVANIA, A CORPORATION OF NEW JERSEY

STEAM SEPARATOR

Application filed June 7, 1926. Serial No. 114,063.

This invention relates to fluid separators, particularly to fluid separators which are very long compared with their capacities and which are composed of several units or sections. The object of the invention is to equalize the pressure in various portions of the separators and to eliminate eddy currents and local currents of gas, steam or liquids, in certain portions of the separator or from one portion of the separator to another. Although my invention applies to various types of separators, yet for the purpose of clearly disclosing the same I have illustrated and described it as applied to the type of steam separator known in the trade as the "Tracy steam purifier", particularly when that type of separator is installed in a steam boiler for the purpose of drying and otherwise purifying the steam.

20 Of the drawings Fig. 1 is an end view of a unit fluid separator or purifier which embodies the features of my invention, with a portion of the end plate broken away; Fig. 2 is a section of the purifier along the line 25 2-2 of Fig. 1, showing a portion of another unit; Fig. 3 is a reduced end view of the separator; Fig. 4 is a reduced elevation of a purifier mounted in a boiler for operation, the purifier consisting of 6 sections; and 30 Fig. 5 is an enlarged central sectional view of a portion of the purifier similar to Fig. 4 comprising 3 sections only.

The separator which I have illustrated is ordinarily installed in a steam boiler 10 and 35 the separator comprises a casing 11 which forms the exterior portion of the separator. To this casing are attached cartons or banks 12 of baffles 13 which dry and purify the steam as it passes from the boiler through 40 the baffles to the interior chambers. From the separator the steam passes out of the boiler through an outlet 14 which is connected to the steam supply main of the boiler. The steam passes from the baffles 13 45 into the interior chamber 15, through the slot passageway 16, into the interior conduit 17, and thence into the separator outlet 8 and the boiler outlet 14.

The interior conduit 17 is enclosed by walls 50 18, forming its sides, and a bottom 19, and

over the chamber is a plate 20 which is elevated above the side walls so as to form the slot 16 through which the steam enters the interior conduit. In practice the separators are of considerable length and frequently 55 comprise several unit casings or sections connected end to end in series, as indicated in Fig. 4 which illustrates three sections on one side of the outlet and corresponding sections on the other side of the outlet. The 60 slots 16 extend substantially the full length of each section and form inlets for the steam passing from the chamber 15 to the chamber 17. The baffles extend substantially from the steam outlet 8 to the remote end of the 65 farthest section. The steam, however, entering this slot inlet 16 must all pass through the conduit 17 to the outlet 8.

As a consequence of this arrangement, there is a tendency for the steam to pass through 70 the baffles more rapidly as the outlet is approached, because of the back pressure generated in the chamber 17 being less nearer the outlet. To offset this it has been found desirable to taper the slot inlet 16 by decreasing the width of the slot as the outlet is approached so as to restrict more and more the flow of the steam into the interior conduit. In practice this has been done by increasing the inclination of each plate 20 from section 75 to section, having the inclination of the plate of the second section more than that of the first section and of the third section more than that of the second, and so on. In Fig. 5 I have shown three sections with this varying 80 inclination of the plate 20. In practice I prefer to have the plate 20 as well as the side walls 18 of the interior steam chamber terminate a material distance from the outer end of the section most remote from the outlet, 85 as indicated in Fig. 5. In this way the rate of flow through the baffles in the different sections is more nearly equalized.

With long separators, particularly those composed of several sections 21, as they have 90 been made in the past, eddy currents are likely to be set up by pockets or recesses in the sides of the inner conduit 17. The ends of the sections which are connected have end plates 55, with openings 33 in their central 95

portions, so as to form a passageway from one chamber 17 to the next. It is usual to form the ends of the separators with the outer projecting flanges 35 between which are gaskets 36 to prevent leakage into the interior of the separator. To eliminate the pockets or recesses 34 where the two ends of the sections abut, I provide inner flanges 37 and 38 and 39, which extend to the gaskets and which are substantially flush with the inner surfaces of the conduit 17, thus eliminating the recesses which would otherwise be formed between the ends of the conduits of each pair of sections. In this manner the steam entering the separators through the inlets 16 into the inner conduits flows without disturbance along the conduits to the outlet 8 of the separator, thus eliminating eddy currents, and more uniformly distributing the back pressure in the conduit so as to more uniformly equalize the flow through the inlets 16 and thus through the purifying baffles.

To further equalize the pressure throughout the entire length of the separator I provide openings 40 in the partitions 41 in the abutting ends of the separators, so that the steam, in the passageways 15 surrounding the inner conduit 17, is at liberty to flow freely from one section 21 of the separator to another without passing into the inner conduit. If, for instance, the pressure in these outer passageways in the section most remote from the outlet 8 is greater than the pressure in a section nearer the outlet, there will be a flow of steam, from the remote section to the nearer one, in the passageway 15, and this will reduce the back pressure in the remote section and will allow the steam to flow more freely through the baffles into that section, and thus will produce more uniform flow through the baffles. It will, of course, be obvious that, in producing uniform flow through the baffles, it is immaterial whether the steam, after passing through the baffles, flows towards the outlet 8 through the outer passageways 15 or the inner conduit 17. On the other hand, if the flow through the baffles adjacent the outlet is hindered too much by the back pressure there will be a tendency for the steam to flow outwardly in the passageway 15 until it passes into the inner conduit, thus also equalizing the flow through the baffles.

As is well understood, it is common in separators to have drain pipes 50 to carry off the water which is separated from the steam and which flows downwardly from the baffles into the water passageway 51. This separated water flows from each section into a manifold drain pipe 52, and thus out of the boiler if desired. I have found that there may be local currents set up in these drain pipes and the passageways 51, owing, presumably, to various variations in steam or air pressure at different points, and partly, perhaps,

to the entrained steam which at times is carried downwardly into the drain pipe. These local currents may interfere with the capacity of the water system and may be otherwise objectionable. Equalizing the pressure, in the manner hereinabove described, tends to assist in eliminating these local currents, and I have found it desirable, in some cases, to provide openings 53 in the partitions 54 at the ends of the sections, so that the water or the steam is at liberty to flow from one section to another through these openings and the pressure in the various passageways 51 is thus substantially equalized.

It is to be understood that the sections or units 21 of the separator are connected together by means of flanges 55 and that each section or unit is in general similar to each of the others. One purpose of so forming the separator of a plurality of short units instead of making a single unit of sufficient length, is for convenience in handling, installing, and the like. Provision may thus be made for boilers of various sizes and capacities by the use of varying numbers of standard units.

I claim as my invention:

1. A steam separator comprising a plurality of unit casings connected end to end in series, and having a steam outlet adjacent one end of the series, an inner longitudinal steam conduit extending substantially from one end to the other of said series of units, the inner surfaces of each of the side walls of said conduit extending continuously from one end to the other and in substantially the same plane.

2. A steam separator according to claim 1, in which steam purifying baffles are mounted outside of said conduit and extend from substantially one end to the other and are spaced away from said conduit, whereby a passageway is formed between said baffles and said inner conduit.

3. A steam separator according to claim 1, in which the steam conduit of each unit has a steam inlet running substantially from one end to the other of said unit, the side walls of said conduit terminating a material distance from the end of the conduit most remote from said outlet.

4. A steam separator according to claim 1, in which steam purifying baffles are mounted outside of said conduit and extend from substantially one end to the other and are spaced away from said conduit, whereby a passageway is formed between said baffles and said inner conduit, said passageway being continuous from substantially one end to the other of said separator.

5. A steam separator comprising a plurality of unit casings connected end to end in series, each of said casings having an end plate by means of which said units are connected, each of the end plates which is connected to another end plate having an open-

ing through its central portion, inner flanges surrounding said opening and projecting angularly outwardly a material distance from the end plate and registering with similar flanges on the end plate of the adjacent casting, the inner surfaces of said flanges being substantially flush with the edges of said openings.

6. A steam separator according to claim 5, in which outer flanges project outwardly from the outer edges of said end plates, and other flanges projecting outwardly from each end plate, said other flanges extending transversely from the outer ends of the respective top and bottom flanges surrounding said opening to the said flanges on the outer edges of said plates, said end plates having openings therethrough on each side of said central opening between said outer and inner flanges.

7. A gas separator comprising a plurality of unit casings connected end to end in series, each of said casings having an end plate by means of which it is connected to an end plate of an adjacent casing, each of the end plates so connected having an opening through its central portion registering with the corresponding opening of the adjacent end plate, and each of said end plates having an opening at one side of said central opening registering with the corresponding opening in the adjacent end plate.

In testimony whereof, I hereunto set my hand.

35 GRANT D. BRADSHAW.
